Patented Jan. 28, 1975

234,168

HAIR BRUSH

Walter Sporn, 18240 Harwood Ave.,
Homewood, Ill. 60430

Filed Dec. 17, 1973, Ser. No. 425,096

Term of patent 14 years

Int. Cl. D4—02

U.S. Cl. D4—35

FIG. 1

FIG. 2

FIG. 3

FIG. 4

FIG. 5

FIG. 6

FIG. 1 is a top perspective view of a hair brush illustrating the design of the invention;

FIG. 2 is an elevational view of one end thereof;

FIG. 3 is a side elevational view thereof;

FIG. 4 is a top plan view thereof;

FIG. 5 is an elevational view of the end thereof opposite the end shown in FIG. 2; and

FIG. 6 is a bottom plan view thereof.

I claim:

The ornamental design for a hair brush, substantially as shown.
